UNITED STATES PATENT OFFICE.

GRACE E. WINTERHALDER, OF KAMLOOPS, BRITISH COLUMBIA, CANADA.

SUSPENDER CONNECTION TO STOCKINGS.

Application filed March 24, 1922. Serial No. 546,498.

To all whom it may concern:

Be it known that I, GRACE E. WINTERHALDER, a citizen of the Dominion of Canada, residing at Kamloops, in the Province 5 of British Columbia, Canada, have invented certain new and useful Improvements in Suspender Connections to Stockings, of which the following is a specification.

This invention relates to a means for connecting a stocking suspender or the like to the stocking, or to such other fabric as it is desired to suspend or connect.

Devices of this kind, which are at present in the market, are positive in their grip, but 15 subject the fabric to such severe local strain that it is rapidly torn and destroyed.

The device, which is the subject of this application, is designed to be no less effective in its hold, but retains the fabric without undue strain on the material.

The invention is particularly described in the following specification, reference being made to the drawings by which it is accompanied, in which:

25 Fig. 1 is a side elevation of the device to an enlarged scale, showing it in position for the reception of the upper edge of the stocking or other article.

Fig. 2 is a similar view showing the device in the position of grip.

Fig. 3 is a perspective view of the device in the open or release position.

Fig. 4 is a face view showing the clasp in the closed or grip position of Fig. 2.

35 Fig. 5 shows its application as a garter or stocking support.

Fig. 6 shows in cross section the position of the fabric in the clasp to an enlarged scale.

40 The device consists of three connected cooperative parts, a lever 2, 3, 4, one end of which is connected to the flexible tape 5 of the garter or suspender, a retaining loop 6 connected to the other end 2 of the lever, 45 and a hook 8, 9 connected to the lever intermediate its ends and extending downward that the lever and its retaining loop when straight, may lie within the bend of the hook.

These parts, the lever, the retainer and the 50 hook, are preferably bent from relatively strong, non-corrodible wire, or from wire, coated with non-corrodible metal or with enamel.

55 The lever has a relatively wide, straight, barred end loop 2, from the ends of which the sides are inwardly turned toward one

another and are thereafter outwardly turned as at 3 and therefrom are bent together and the ends are inserted and secured in a metal sleeve or clasp 4. Around this sleeve 4 the 60 tape or elastic 5 of the suspender or garter is sewn.

To the loop end 2 of this lever portion the ends of the retaining loop 6 are closely bent, as at 7, to turn freely thereon.

65 The hook 9 is formed on the end of a loop, the ends of the sides 8 of which are connected to the bends 3 of the lever member. The length of the hook from its connections to the bends 3 of the lever member to the inside of its bend 9 is such that when the lever and the retainer are pressed against the shank of the hook, they will be straight and will exert sufficient endwise pressure to retain the fabric of the stocking tightly in the 75 hook.

The width of the hook 8, 9 is less than that of the lever 2, 4 and of the retainer 6, and the end of the hook and the end of the retainer are increased slightly in width to 80 afford an ample bearing contact with the fabric.

It will be noticed that the fabric is not only retained in the hook by the straightening or toggle action of the lever and its connected loop, but the tension of the suspender tends to hold it in that retaining position against any tendency to release that there may be, and the fabric is not unduly stretched or strained in such retention.

90 Having now particularly described my invention, I hereby declare that what I claim as new and desire to be protected in my Letters Patent, is:

Claims:

1. A suspender fastening, comprising a wire loop, the loop end of which is bent to form a hook and the free ends of which are bent to form eyes, a lever member bent to form a loop, the loop end of which is a straight bar and the free ends of which are bent at right angles toward one another and intermediate the loop and the free end the wire is offset inward and passed through the eyes of the hook, a tubular sleeve fitted on the inwardly turned free ends of the lever member, and a retaining member bent as a loop, the slightly convexed loop end of which is wider than the loop of the hook and the free ends of which are bent as eyes to fit on the straight bar of the lever member.
2. A suspender fastening, comprising a

hook member formed of a loop of wire, the loop end of which is upwardly turned to form a hook, and the free ends of which are bent to form eyes, a lever member of wire formed as a loop, the loop end of which is a straight bar longer than the width of the hook member and the free ends of which are inwardly turned toward one another and intermediate the loop and the inwardly turned ends the wire is inwardly turned to form shoulders fitting the eyes of the hook, a tubular sleeve connecting the inwardly turned ends of the lever, and a retaining member of wire formed as a loop, the loop end of which is wider than that of the hook, and is slightly convexed, the free ends of which retaining member are turned to form eyes around the bar of the lever member.

3. A suspender fastening, comprising a loop of wire, the loop end of which is bent to form a hook and the free ends of which are bent to form eyes, a lever member bent to form a loop, the loop end of which is a straight bar having a length greater than the width between the sides of the loop of the hook, the free ends of which are inwardly turned toward one another and the sides of which, intermediate the loop and the inwardly turned ends, are pivoted in the eyes of the hook, a tubular sleeve connecting the inwardly turned ends of the lever member, and a retaining loop, the free ends of which are pivotally connected to the loop end of the lever member.

In testimony whereof I affix my signature.
GRACE E. WINTERHALDER.
